PNEUMATIC AND LIKE TOOL

John Arthur, Camborne, England, assignor to
 Holman Brothers Limited, Camborne, England,
 a British company

Application October 7, 1932, Serial No. 636,619
 In Great Britain January 13, 1932

10 Claims. (CL 121—19)

This invention consists of improvements in or relating to pneumatic and like tools.

Fluid-driven tools (such as pneumatic hammers) have already been proposed having a working cylinder, a free piston therein, a plate or disc valve for controlling admission of driving fluid alternately to opposite ends of the cylinder, and one or more exhaust ports to be covered and uncovered by the piston; and in this specification 10 the expression "a fluid-driven tool of the type described" is intended to cover such tools.

An object of my invention is to ensure in a fluid-driven tool of the type described that excess fluid pressure detrimental to the operation 15 of the tool is not built up in front of the piston during its travel in one or the other direction, and to this end the invention provides a fluid-driven tool of the type described with fluid distributing means comprising in combination a 20 main valve having two faces opening to opposite ends of the cylinder, an annular auxiliary beat valve and valve casing wherein said auxiliary valve is axially movable, two fluid passages which lead from one and the same face of 25 the auxiliary valve to one end of the cylinder and to exhaust respectively, and a third fluid-passage leading from the other face of the auxiliary valve to that face of the main valve which also opens to the same one end of the cylinder.

30 A further object of the invention is to ensure in the construction of fluid-driven tool described in the foregoing paragraph the delivery of an uncushioned blow by the piston when making its forward or striking stroke, and the two fluid- 35 passages which lead from one and the same face of the auxiliary valve are then arranged to pass respectively to exhaust and to the forward end of the cylinder, that passage passing to the forward end of the cylinder being joined by a further fluid-passage having branched fluid-passages leading to the opposite face of the auxiliary valve and one face of the main valve respectively.

It is an alternative object of the invention 45 when the tool is such that the piston stroke is substantially in excess of the length of the piston to ensure full travel of the piston on its return stroke and accordingly the two fluid-passages leading from one and the same face of 50 the auxiliary valve then pass respectively to exhaust and to the rearward end of the cylinder at a point in the length thereof distant from the actual rearmost point to an extent which is less than the length of the piston, while a third 55 fluid-passage passes from the other face of the

auxiliary valve and joins the fluid-passage leading from one face of the main valve to the rearward end of the cylinder.

It is also an object of the invention to reduce vibration in tools of the type described and particularly to reduce vibration or fluttering of the main valve and all tools constructed in accordance with the invention may, therefore, employ a plate or disc valve of the general type having in addition to the two working faces of the valve, 65 an axial extension of smaller diameter than the disc, and such a valve is conveniently arranged to be moved from one beat to another partly by pressure built up by motion of the piston and partly by driving fluid-pressure.

70 It is a further object of the invention to reduce in some instances the overall length of a fluid-driven tool of the type described to a minimum, and the fluid distributing means in such a tool are then disposed in an annular space 75 between the casing of the tool and an inner rearward extension of the cylinder, which extension has ports near its rearward end to allow of communication between the rearward end of the cylinder and the main valve. The main and 80 auxiliary valves and valve casings therefor are in such a construction preferably all of annular form.

85 Subsidiary objects in the various constructional forms of the invention are the isolation of the valves from contact with the piston and the provision of an arrangement which is easy to assemble and economical in manufacture.

The accompanying drawings illustrate by way of example various forms of pneumatic hammer 90 embodying this invention.

95 Figures 1 and 1a together illustrate a hammer the several parts of which are shown, some out of position in order to be in one plane; and at 9—9 the parts are a section on the line IX—IX of Figure 9 and at 10—10 are a section on the line X—X of Figure 10;

100 Figure 2 is a part longitudinal section of the valve end taken on a different plane from Figure 1;

105 Figure 3 is a part longitudinal section of an alternative form of pneumatic hammer in which provision is made for avoiding excessive building up of pressure behind the piston on its return stroke;

110 Figure 4 is a part longitudinal section of the alternative form shown in Figure 3 but taken in a different plane;

Figure 5 is a longitudinal section of the valve

mechanism showing alternative arrangement of the main valve;

Figure 6 is a longitudinal section of valve mechanism showing a further alternative arrangement of the main valve;

Figure 7 shows a pneumatic hammer specially arranged to reduce the overall length to a minimum while allowing for a long piston stroke;

10 Figure 8 is a detailed view of the same in that part of the valve box with which the auxiliary valve contacts;

Figure 9 is a section on the line 9—9 of Figure 1, and

15 Figure 10 is a section on the line 10—10 of Figure 1.

Referring first to Figures 1 and 2, 1 is the main distribution valve, 2 is the auxiliary valve in the form of an annular disc, 3 is the piston, 4 is the cylinder, 5 the valve box, 6 the auxiliary valve box, 7 the cylinder cover, and 8 the handle which constitutes a casing around the valve boxes.

Compressed air enters via port 9 into recess 10 and (as shown in Figure 2) fills ports 11 and 12 and annular recesses 13 and 14. Compressed air also passes through orifice 15 in the main valve 1 into the cavity 16 thereof.

Assuming that the components of the hammer are in the position shown in Figure 1 compressed air will now pass between the rear face of the main valve 1 and its rear seat 17 into the annular recess 18 which communicates with the forward end of the piston 3 through passages 19, 20 and 21, thus driving the piston rearwardly, this air exhausting to atmosphere through ports 22 and 25 and passages 23 and 24, as the forward end of the piston successively uncovers the ports 22 and 25 on its rearward stroke. During the rearward stroke of the piston and after its rear edge covers the port 25, compression of air in the rearward or inner end of the cylinder exerts pressure on the forward face of the valve 1 by means of the annular groove 26 and ports 27 in the cylinder cover 7, and this pressure increases. When the forward edge of the piston uncovers the port 22, the rear face of the main valve 1 is released to atmosphere through passage 21 and port 22 so that the built up pressure is enabled to force the main valve into the position shown in Figure 2.

In this position compressed air is now free to enter the rear end of the cylinder from recess 14 and ports 27 to drive the piston forward on its striking stroke. This air exhausts to atmosphere through port 25 and passages 23 and 24 just prior to the impact of the piston; and owing to this reduction of pressure in the cylinder, the positive pressure on the small end of the main valve 1 forces the main valve on to its forward seating 28 and cuts off the compressed air from the rear end of the cylinder whereupon the cycle again commences.

Turning to the auxiliary valve 2 it will be noted that its rear face controls an exhaust port 46 and a port 30 leading not only to the forward end of the cylinder but communicating also through passage 19 with the ports 29 and annular channel 29^a on the forward side of the auxiliary valve 2 and also with the annular recess 18. That is to say, both forward and rear faces of the auxiliary valve 2 communicate with the forward end of the piston, and also with recess 18 by means of the ports 29, 30, 31, 19, 20 and 21. The area of the forward face of the valve 2 exposed to any pres-

sure in these ports or rather in the annular channel 29^a is slightly greater than the area of the rear face exposed to any pressure in port 30 so that when compressed air is admitted into recess 18 by the main valve 1 and thus into ports 19, 20 and 21, this pressure acts on the forward face of the auxiliary valve 2 and forces it against its rear seat thus closing ports 30 and 46. However, during the working stroke of the piston any compression in front of the piston takes the line of least resistance to exhaust and as the passage 19 and port 29 together form a more restricted path for the built up pressure than the port 30, the auxiliary valve 2 is moved forward thus connecting the port 30 with the exhaust port 46. In other words the position and size of the ports is such as to ensure that the auxiliary valve 2 moves in a direction opposite to the main valve 1. The port 15 in the small end of the main valve 1 and the cavity 16 are of such a diameter that the resultant pressure acting on the end of valve 1 can be made to control the speed of the piston as required. Other methods of securing this small positive pressure on the small end of the valve are shown in Figures 5 and 6.

In Figure 5 the main valve 1 has no internal cavity but a small chamber 34 is formed between the end of the valve and the main valve box 5 which is fed by a restricted passage 33.

In Figure 6 a restricted passage 35 in the end of the valve box 5 feeds the cavity 36 between the valve 1 and the box and during the forward stroke of the piston only a leak is allowed into the cylinder by means of a slightly smaller passage 37 through the main valve.

The construction shown in Figures 1, 2, 5 and 6 applies to all the cases where it is desired that the auxiliary valve shall relieve the compression set up by the piston in the forward end of the cylinder in tools of exceptionally long stroke much in excess of the piston. It may however be necessary to relieve the pressure in the rear end of the cylinder (at least during part of the return stroke) so as to ensure that the piston returns fully on its rear stroke. Figures 3 and 4 illustrate an alternative arrangement according to the invention in which the auxiliary valve controls special ports to secure this result.

Referring to Figures 3 and 4 the compression in the rear end of the cylinder is relieved by means of port 42 which is disposed near the rear end of the cylinder (i. e. less than a piston's length from the cylinder end). This port when uncovered connects the inner end of the cylinder through passages 41, 40, 31 and 30^a to the rear face of the auxiliary valve 2 and thence as before to the exhaust port 46 shown in Figure 1. The position of port 42 is such that when the piston does cover it on its rear stroke there will be sufficient compression set up in the cylinder to reverse the main valve through port 27 and also to reverse the auxiliary valve 2 through passages 39, 38, 43 and 29 and annular channel 29^a. During the forward stroke of the piston the auxiliary valve will be firmly held on its rear seating by the incoming compressed air from recesses 14 and 26, port 27 and passages 39, 38, 43 and 29, thus keeping the port 30^a closed during the forward stroke of the piston. The compressed air to return the piston on its rear stroke passes from recesses 13 and 18 through ports 44, 45 and 21 as shown in Figure 4.

Referring to Figures 7 and 8, 1 is the main distributing valve, 2 is the auxiliary valve, 3 is the piston, 4 is the cylinder, 5 is the valve

box, 46 is the cylinder cover, 47 is the valve box cover and 8 is the handle. Air under pressure enters the air port 9 in the handle 8 into chamber 10 and fills ports 11, 12 and 13 and annular recesses 14 and 15. Assuming the component parts of the tool are as shown in Figure 7, compressed air will pass between the forward face of the main valve 1 and the valve seating 48 into the annular recess 49 and from that recess 10 into port 50 and annular groove 51. The air in this groove exerts pressure on the rear face of the auxiliary valve 2 and holds it on its forward seating 52 to close the exhaust ports 53 communicating between this seating 52 and the 15 exhaust passages 54, 55 in the cylinder 4. Air will pass from port 50 into passage 56 by way of passages 57 and 58 and through cylinder port 59 forcing the piston on its rearward stroke. When the front end of the piston has uncovered 20 the main exhaust port 60 the compressed air in the front end of the cylinder and in passage 56 and port 50 and recess 49 is exhausted to atmosphere and consequently the pressure in ports 11 and the compression developed by the 25 return of the piston exerting pressure through cylinder ports 61 on the face of the main valve exposed in the cavity 62 overcomes the small positive pressure on the small end of the main valve 1 which has been holding that valve on its 30 rear seat during the backward stroke of the piston, and forces the main valve 1 into the forward position thus closing the supply of air into the recess 49. Air will now flow through ports 11 across the rear seat of the main valve 1 into 35 the cavity 62 and thence through ports 61 into the rear end of the cylinder, driving the piston forward on its striking stroke. When the rear end of the piston uncovers the main exhaust port 60, the compressed air which has been driving 40 the piston forward and holding the main valve in its forward position is exhausted to atmosphere and the positive pressure exerted on the forward end of the valve in recesses 14 and 15 reverses the main valve, whereupon the cycle again commences.

During the forward or striking stroke of the piston, all compression of air on the front of the piston is relieved by means of the auxiliary valve 2, because the position of this auxiliary valve 50 is reversed. The reason for this reversal is that any pressure built up in the front of the piston acts in the recesses 63. The area of the auxiliary valve 2 exposed to this pressure in recesses 63 is slightly less than the area in recess 51 on 55 the opposite side, but as the pressure will take the line of least resistance to exhaust, it will exhaust itself across the forward face of the valve 2 from recesses 63 to exhaust ports 53 which are 60 open to atmosphere through passages 54 and 55. It will thus be seen that the piston gives an uncushioned blow up to the moment of impact.

Referring to Figures 9 and 10 it will be seen that the handle portion in which the passage 65 9 is formed is screwthreaded on to the main cylinder and the parts are maintained in adjustment by means of a ring 70 having a splined engagement with the outer surface of the cylinder so as to be axially movable thereon and having a locking tooth 71 which can enter one or the other of the spaces between teeth 72 formed on the opposed surface of the handle member according to the angular adjustment of the latter. The tooth 71 is held in between teeth 72 by means 75 of a spring ring 73 having inturned margins

which overhang shoulders on the handle member and on the ring 70 respectively.

As seen in Figure 10 an exhaust air deflector 80 has a spring 81 attached to it by means of rivets 82. The spring 80 has its free end formed to engage in a recess such as 83 to retain the deflector in position.

I claim:—

1. For a fluid driven tool of the type described comprising a working cylinder, a free piston therein and one or more exhaust ports to be covered and uncovered by the piston, fluid distributing means comprising in combination a main valve having two faces opening to opposite ends of the cylinder, an annular auxiliary beat valve and valve casing wherein said auxiliary valve is axially movable, two fluid passages which lead from one and the same face of the auxiliary valve to one end of the cylinder and to exhaust respectively, and a third fluid passage leading from the other face of the auxiliary valve to that face of the main valve which also opens to the same end of the cylinder.

2. For a fluid driven tool of the type described comprising a working cylinder, a free piston therein and one or more exhaust ports to be covered and uncovered by the piston, fluid distributing means comprising in combination a main valve having two faces opening to opposite ends of the cylinder, an annular auxiliary beat valve and valve casing wherein said auxiliary valve is axially movable, and two fluid passages which lead from one and the same face of the auxiliary valve to the forward end of the cylinder and to exhaust respectively, the first of which passages is joined by a third fluid passage having branched fluid passages leading to the opposite face of the auxiliary valve and one face of the main valve respectively.

3. For a fluid driven tool of the type described comprising a working cylinder, a free piston therein and one or more exhaust ports to be covered and uncovered by the piston, fluid distributing means comprising in combination a main valve having two faces opening to opposite ends of the cylinder, an annular auxiliary beat valve and valve casing wherein said auxiliary valve is axially movable, two fluid passages which lead from one and the same face of the auxiliary valve to the forward end of the cylinder and to exhaust respectively, the first of which passages is joined by a third fluid passage having an opening at the opposite face of the auxiliary valve of greater cross-sectional area than that of the opening of the said first fluid passage at the auxiliary valve, and a branched fluid passage from said third passage leading to one face of the main valve.

4. For a fluid driven tool of the type described comprising a working cylinder, a free piston therein and one or more exhaust ports to be covered and uncovered by the piston, fluid distributing means comprising in combination a main valve having two faces opening to opposite ends of the cylinder, a valve box wherein an axial extension of the main valve perpendicular to the valve faces is slidably mounted, an auxiliary beat valve constituted by a flat annular ring mounted coaxially with the main valve in an annular chamber with which the inner and outer peripheral walls of the ring make a sliding fit, two fluid passages which lead from one and the same face of the auxiliary valve to one end of the cylinder and to exhaust respectively, and a third fluid passage leading from the other face of the auxiliary

valve to that face of the main valve which also opens to the same end of the cylinder.

5. For a fluid driven tool of the type described comprising a working cylinder, a free piston therein and one or more exhaust ports to be covered and uncovered by the piston, fluid distributing means comprising in combination a main valve having two faces opening to opposite ends of the cylinders, an annular auxiliary beat valve and valve casing wherein said auxiliary valve is axially movable, two fluid passages which respectively lead from one and the same face of the auxiliary valve to exhaust and to the rearward end of the cylinder at a point in the length thereof distant from the actual rearmost point by a length which is less than the length of the piston, and a third fluid passage which leads from the other face of the auxiliary valve and joins a fluid passage leading from one face of the main valve to the rearward end of the cylinder.

6. For a fluid driven tool of the type described comprising a working cylinder, a free piston therein and one or more exhaust ports to be covered and uncovered by the piston, fluid distributing means comprising in combination a main valve having two faces opening to opposite ends of the cylinder, a valve box wherein an axial extension of the main valve perpendicular to the valve faces is slidably mounted, an auxiliary beat valve constituted by a flat annular ring mounted coaxially with the main valve in an annular chamber with which the inner and outer peripheral walls of the ring make a sliding fit, two fluid passages which respectively lead from one and the same face of the auxiliary valve to exhaust and to the rearward end of the cylinder at a point in the length thereof distant from the actual rearmost point by a length which is less than the length of the piston, and a third fluid passage which leads from the other face of the auxiliary valve and joins a fluid passage leading from one face of the main valve to the rearward end of the cylinder.

7. For a fluid driven tool of the type described comprising a working cylinder, a free piston therein and one or more exhaust ports to be covered and uncovered by the piston, fluid distributing means disposed in an annular space between the casing of the tool and an inner extension of the cylinder and comprising in combination a main valve having two faces opening to opposite ends of the cylinder, an annular auxiliary beat valve and valve casing wherein said auxiliary valve is axially movable, two fluid passages which lead from one and the same face of the auxiliary valve to one end of the cylinder and to exhaust respectively, a third fluid passage leading from the other face of the auxiliary valve to that face of the main valve which also opens to the same end of the cylinder, and ports which are provided near the inner end of said cylinder extension to allow communication between the inner end of the cylinder and the main valve.

8. For a fluid driven tool of the type described comprising a working cylinder, a free piston therein and one or more exhaust ports to be covered and uncovered by the piston, fluid distributing means disposed in an annular space be-

tween the casing of the tool and an inner extension of the cylinder and comprising in combination a main valve having two faces opening to opposite ends of the cylinder, a valve box wherein an axial extension of the main valve perpendicular to the valve faces is slidably mounted, an auxiliary beat valve constituted by a flat annular ring mounted co-axially with the main valve in an annular chamber with which the inner and outer peripheral walls of the ring make a sliding fit, two fluid passages which lead from one and the same face of the auxiliary valve to one end of the cylinder and to exhaust respectively, a third fluid passage leading from the other face of the auxiliary valve to that face of the main valve which also opens to the same end of the cylinder, and ports which are provided near the inner end of said cylinder extension to allow communication between the inner end of the cylinder and the main valve.

9. For a fluid driven tool of the type described comprising a working cylinder, a free piston therein and one or more exhaust ports to be covered and uncovered by the piston, fluid distributing means comprising in combination a main valve having two faces opening to opposite ends of the cylinder, a valve box wherein an axial extension of the main valve in a direction perpendicular to the valve faces is slidably mounted, an annular auxiliary beat valve located on that side of the main valve remote from the valve face which opens to the rearward end of the cylinder and valve casing wherein said auxiliary valve is axially movable, two fluid passages which lead from one and the same face of the auxiliary valve to one end of the cylinder and to exhaust respectively, a third fluid passage leading from the other face of the auxiliary valve to that face of the main valve which also opens to the same end of the cylinder, and a fluid passage connecting the fluid supply line with the end surface of the extension piece of the main valve.

10. For a fluid driven tool of the type described comprising a working cylinder, a free piston therein and one or more exhaust ports to be covered and uncovered by the piston, fluid distributing means comprising a main valve having two faces opening to opposite ends of the cylinder, a valve box wherein an axial extension of the main valve in a direction perpendicular to the valve faces is slidably mounted, an auxiliary beat valve located on that side of the main valve remote from the valve face which opens to the rearward end of the cylinder and constituted by a flat annular ring mounted co-axially with the main valve so as to surround the extension thereof in an annular chamber with which the inner and outer peripheral walls of the ring make a sliding fit, two fluid passages which lead from one and the same face of the auxiliary valve to one end of the cylinder and to exhaust respectively, a third fluid passage leading from the other face of the auxiliary valve to that face of the main valve which also opens to the same end of the cylinder, and a fluid passage connecting the fluid supply line with the end surface of the extension piece of the main valve.

JOHN ARTHUR.
